LLP(57) **CLAIM**

The ornamental design for a pressed shredded potato product, as shown and described.

DESCRIPTION

FIG. 1 is a top plan view of a pressed shredded potato product.

FIG. 2 is a bottom view of the pressed shredded potato product of FIG. 1.

FIG. 3 is a left side elevation view of the pressed shredded potato product of FIG. 1.

FIG. 4 is a right side elevation view of the pressed shredded potato product of FIG. 1.

FIG. 5 is a front elevation view of the pressed shredded potato product of FIG. 1.

FIG. 6 is a rear elevation view of the pressed shredded potato product of FIG. 1.

FIG. 7 is an isometric view of the pressed shredded potato product of FIG. 1; and,

FIG. 8 is a cross-sectional front elevation view of the pressed shredded potato product of FIG. 1, taken on the line 8-8 in FIG. 1.

Portions of FIGS. 1 through 8 are shown in broken lines, dash-dot-dash boundary lines, and cross-sectional hatching illustrating portions of the article that form no part of the claimed design.
